Inventor:

Charles Adams Jr.,
By his Atty, J. M. Richards,

UNITED STATES PATENT OFFICE.

CHARLES ADAMS, JR., OF WEEHAWKEN, NEW JERSEY.

DRY-PIPE VALVE.

Application filed June 9, 1920. Serial No. 387,735.

To all whom it may concern:

Be it known that I, CHARLES ADAMS, Jr., a citizen of the United States, residing in Weehawken, in the county of Hudson and State of New Jersey, have invented certain new and useful Improvements in Dry-Pipe Valves, of which the following is a specification.

This invention relates to dry valves which are utilized in dry pipe systems, and comprises a housing generally of the type heretofore known, which housing is provided with hand holes, not shown, for manually closing the valve and for cleaning out purposes.

A principal feature of my device is the new and improved valve action control means whereby the valve is held locked ready for instant release; is capable of quick and easy manual closure; automatically cares for all leakage and slight variations of water pressure; is simple in construction, and has a new feature in a combined valve seat, both seats performing in single function to a single end, although the individual functions of each valve are for different purposes. This feature is new and is not shown at the present time in any type of wet or dry valve.

Another feature and economic advantage is that in dry valves of this type, the valve housings are very large on account of the intricate, heavy and ungainly valve mechanisms heretofore used, whereas, in the present structure, the valve is so compact and simple that it requires less space to properly operate in and therefore the valve body or housing is made correspondingly smaller, thereby requiring a smaller quantity of iron to be utilized therein and thereby tying up less metal for a given purpose.

These and other features and capabilities of my invention will be disclosed in the course of the following description.

Referring to the accompanying drawings forming part of this specification,

Figure 1 is a vertical section of my device.

Figure 2, is a fragmentary enlarged vertical section of the lower portion of my device.

Figure 3 is a plan view on the line 3-3 of Fig. 2.

Figure 4, is a fragmentary cross-sectional view of one of the combined valves showing a valve movement expediting feature thereof.

Figure 5 is a detail vertical sectional view of one of the diaphragms showing its arrangement and attachment to co-operating parts of the device.

Similar reference characters or numerals denote similar parts throughout the several views.

In the present invention the main valve 1, which is an air-valve is carried by a pivot 2 supported by suitable lugs 3, which are or may be integral with the housing 4. The housing 4 has an opening A therein whereby air pressure in the chamber 5 of the main housing 4 may pass therethrough, there to react upon the convoluted or accordion diaphragm 6 which is firmly connected to the valve member 1 at 7 with an air-tight fit, and the lower end of the said diaphragm being also firmly connected at 8 with a non-flexible floating-disk or diaphragm member 9. It will therefore be noted that the non-flexible disk or diaphragm member 9 constitutes a closure for the opening between the valve seats D D' later mentioned, the said convoluted or accordion diaphragm 6 coacting with these two elements to make such closure extensible. The valve member 1 is provided with an inclined seat B which contacts with a corresponding inclined valve seat D upon the housing member and is provided with a rubber, or other like flexible washer-closure member E therein, the said member E being carried by the valve member 1 by reason of being rigidly affixed thereto and held in position by a metal washer 10 which may be riveted or screwed in a suitable manner. The extended edge of the washer-closure member E because of its flexibility permits downward movement of the valve member 1 and yet maintains an air-tight connection between the valve member 1 and the inclined seat D, and at its opposite edge E' engages the seat D' substantially similarly to the seat D.

The floating closure-disk 9 is arranged to threadedly receive therein the tapered shank 11 of a toggle bar 12, the lower end of which is so grooved or contoured as at 12',

to carry the inner ends 13 of a plurality of toggle arms 14 and to operate the same toggle arms by an action of the floating closure member 9 which will be hereinafter described. The toggle-arms 14 are held in position in the contoured portion or groove 12 by the tension of a circular split spring S, which engages projections or stops 15, Fig. 3, located about midway of the toggle arms.

The outer ends 16 of the toggle arms 14 extend through a lever-collar, later described, and are arranged for engagement with a locking-groove 17 which is located in the water duct or chamber generally denoted by F, which is at the water side of the dry valve housing and near the upper end thereof.

Adjacent the said locking or toggle groove 17 is arranged a second valve seat 18 upon which is seated a toggle valve or disk 19 having a downwardly extending toggle lever collar 20 which is provided with a series of apertures or openings 21, Figs. 2 and 3, through which the toggle arms 14 protrude for engagement with the locking-groove 17, and through which apertures 21 the action of the toggle arms at their outer ends is controlled. Between the floating closure member 9 and the water closure disk or valve 19 there is rigidly affixed at the upper end 23 thereof to the disk closure member 9, and at the lower end 24 thereof to the water closure disk or valve 19 in an air-tight manner, a secondary or differential convoluted or accordion diaphragm 22, through the center of which passes the toggle bar or strut 12. This last arrangement permits of free floating action of the toggle bar or strut 12 which is rigidly connected to the disk or floating diaphragm 9, thus effecting a repose of the water valve 19 upon its seat 18. The secondary diaphragm 22, besides acting as a flexible connection between the disk closure member 9 and the toggle valve 19, avoids the use of a water excluding means or stuffing-box for the stem 12, the water being allowed to pass within the diaphragm 22 but being excluded thereby from the chamber 5^A.

It will therefore be observed that there are three main elements combining to valve the water end F of the device from the air pressure chamber 5, and these consist generally in the valve member 1, with its connected floating closure disk member 9, the water closure valve 19, and its floating connection with the said member 9, and the toggle members 14 whereby the entire valve assembly is locked togglewise to the dry valve 1.

It is ordinarily necessary in dry valves for fire extinguishers such as those to which this valve is adapted for use, to have a fluid drain of some kind in the intermediate or atmosphere chamber, but it has never been possible

to place this sort of drain control in valves of the usual well-known construction, whereas, in the present instance, this new and improved type of valve lends itself very readily to the provision of means whereby the chamber 5, known as the atmosphere chamber and which is formed between the elements 1 and 19, may be drained constantly in normal inoperative position whereby to take away leakage of water which may occur between the valve seat 18 and the valve member 19. This drain as Z may be located at the lower point of the valve housing and is controlled by a ball face closure member Y which is seated in the drain opening Z, and, as shown in Fig. 2, it is provided with a lock-groove X near its upper end, which, when the valve 19 is in closed inoperative position, engages with a corresponding contoured lug W located upon the edge of the valve 19. When the valve 19 is in closed inoperative position, holding back the water pressure from the tanks, not shown, the lug W is in engagement with the groove X, Fig. 1, and thereby holding the valve Y from its seat in a limited amount, and in such a manner as to permit the chamber 5^A to be continually open to atmosphere.

A further cooperating means is provided whereby the said valve Y may be held from off the seat, permitting the draining operation to occur, and consists in providing the said valve Y with a lower stem U which may be integral therewith, and a short bent spring V which is affixed by any suitable means to the wall of the housing 4 and bearing against the stem of the valve Y, the effect being that, when the valve Y is in operative position for draining, as shown in Fig. 1, the entire valve Y is thrust to one side of the drain Z, so that, while the groove X of the valve Y is in engagement with the lug W, the stem thereof is also in engagement with the side of the aperture Z through the combined side thrusts of the lug W and the spring V. Upon lowering of the pressure in the air chamber 5, by reason of operation of some of the spreaders or sprinkler heads, not shown, a lifting action of the valve 19 is permitted, and this causes the lug W on the valve 18 to disengage the groove X of the valve Y, the valve Y lifting slightly in the meanwhile and thereafter, due to the pressure of fluid admitted to chamber 5^A, the valve Y is forced downwardly upon its seat, as shown in Fig. 2, thereby closing the chamber 5^A against loss of water through the drain aperture Z. At the same time, if the valve 19 should fall back upon its seat, it will be prevented from making a complete closure by reason of its engagement with the top of the valve Y, as shown at Fig. 2. This action will leave the valve 19 unsealed without full contact with the seat and therefore in position where it must be manually

reset in order to insure its proper action for further use.

To provide for control of the mechanism under loss of air pressure in the chamber 5 which would act to unseat the valves 1 and 19 only partially, or in the event that the toggle-arms 14 for some reason are tardy in releasing but allow partial unseating of these valves, an auxiliary or secondary valve 25 is provided having a stem 26 with an extended upper end 27 which engages a recess 28 in the upper face of the disk-closure member 9, the stem 26 extending downwardly through an aperture in the disk closure member 9 which aperture joins said recess 28. The valve 25 is provided with a head 29, and a spring 30 is arranged around the stem 26 abutting the upper side of the head 29 and the under side of the closure disk-member 9, the tendency of the spring 30 being to force the head 29 down into normal engagement with the upper end of an aperture 31 formed through the valve 19; the purpose being that the pressure of water admitted to the chamber 5^A, due to the partial unseating of the valve 19, will lift the closure member 9 sufficiently to unseat the valve 25 from the aperture 31, the valve 25 being reciprocatable in the aperture and recess 28, and will permit passage of water by means of the aperture 31 into the chamber 5^A, the valve Y normally being open and allowing escape of the atmospheric air from the chamber 5^A, which water by adding to the pressure of the water entering by means of the partially unseated valve 19, together with the water-pressure upon the valve 19 from the chamber F, will completely unseat the valves 19 and 1 for full entrance of water to the chamber 5, the valve Y as the valve 19 is lifted or unseated being thereby seated and preventing escape of the water by the drain Z.

In the modified form of device shown in Fig. 4, the toggle-bar or strut 12 is provided with a disk or valve member 32, located somewhat above the contour or groove 13, which disk or valve member engages a circular recess or seat 33 in the upper face of the valve 19. The secondary or differential diaphragm 22, through the center of which passes the toggle-bar or strut 12, is affixed in an air-tight manner at its upper end to the disk closure member 9 the same as in the other form of my device, but is affixed in air-tight manner at its lower end, as 34, to the ring or valve member 32, the water-pressure valve 25 being omitted in this form of my device, the interior of the diaphragm 22 being open at the bottom but closed at the top, and the purpose of this form being to expedite the entrance of water into the chamber 5^A as soon as the toggle-arms 14 begin to be dislodged or disengaged from the contour or groove 17 through upward move-

ment of the toggle-bar or strut 12, due to the distending or dilating of the diaphragms 22 and 6 upon lessening of the air pressure in the chamber 5, and providing an opening or water admitting movement of the ring or valve member 32 from its seat 33, and thus tending to quicker opening of the valve 19.

In operation the valves 1 and 19 are seated or closed by manual operation through a hand-hole or other suitable opening, not shown, in the housing 4, the diaphragms 6 and 22, thereby being slightly compressed and thus causing downward movement of the toggle-stem 12 and bringing the toggle-arms 14 into camming engagement with the groove of the toggle-stem 12 and with the locking-groove 17 of the water chamber, thereby holding the wet and dry valves closed. Lessening of the air pressure in the pressure chamber 5 allows the diaphragms to extend and move upwardly, thereby disengaging or dislodging the toggle-arms 14 from engagement with the locking-groove 17 and permitting concurrent movement of the valves to open position by pressure of the water from the water chamber. By this arrangement a differential pneumatic and hydraulic controlled means is provided whereby the air supplied to the pressure chamber may be under comparatively small compression exerted upon a greater area of the dry valve and yet be sufficient to hold the wet valve 19 closed against a relatively much greater water pressure exerted upon a less area in an opposite direction upon the wet valve.

Having thus described my invention, it should be understood that there may be modifications thereof and variations therein without departing from the spirit of the invention or exceeding the scope of the appended claims.

Having thus described my invention, I claim:

1. A dry pipe valve comprising a casing having an air inlet and a water inlet in opposed relation to each other, and a differential pneumatic and hydraulic closure valve intermediate of said inlets controlled by collapsible and extensible means normally located in the axial line of said inlets.

2. A dry pipe valve comprising an air inlet and a water inlet in opposed relation to each other, a valve closure means between said inlets, differential pressure locking means carried on said closure means, and collapsible and extensible means normally located in the axial line of said inlets for controlling said locking means.

3. A dry valve comprising an air inlet and a water inlet in opposed relation to each other, a valve closure means between said inlets, differential pressure locking and releasing means carried on said closure means,

- and collapsible and extensible means normally located in the axial line of said inlets for controlling the locking and releasing means.
5. A dry valve of the class described having a dry end and a wet end, a valve closure means between said ends, and differentially controlled locking and releasing means carried on said valve closure means; said locking and releasing means comprising collapsible and extensible diaphragms.
6. A dry valve of the class described having a dry end and a wet end, a valve closure means between said ends, and differentially controlled locking and releasing means carried on said valve closure means; said locking and releasing means comprising collapsible and extensible cooperative diaphragms.
20. 6. A dry valve of the class described having a dry end and a wet end, a valve closure means between said ends, and differentially controlled locking and releasing means carried on said valve closure means; said locking and releasing means comprising collapsible and extensible diaphragms and toggle means operative by said diaphragms.
7. A dry valve of the class described having a dry end and a wet end, and comprising a dry valve for the dry end and a wet valve for the wet end, and means collapsible by pressure and extensible upon lessening thereof said valves being retained in closed position by pressure upon said means, and being concurrently movable to open position upon the lessening of said pressure upon said means.
8. A dry valve of the class described having a dry end and a wet end, comprising a dry valve for the dry end and a wet valve for the wet end, and collapsible and extensible means co-operating with said valves, said valves being movable to closed position, and being retained therein by air pressure upon said collapsible and extensible means and being concurrently movable to open position by water pressure upon lessening of said air pressure upon the collapsible and extensible means.
50. 9. A dry valve of the class described having a dry end and a wet end, and comprising a dry valve for the dry end and a wet valve for the wet end, said dry valve including means susceptible to pressure, and locking and releasing means operative by said means susceptible to pressure; said locking and releasing means being retained in position for locking the valves in closed position by pressure upon said susceptible means and being releasable upon lessening of said retaining pressure for permitting concurrent movement of the valves to open position.
10. A dry valve of the class described hav-
- ing a dry end and a wet end, and comprising a dry valve for the dry end and a wet valve for the wet end, said dry valve including means susceptible to air pressure and to water pressure, and locking and releasing means operative by said means susceptible to pressure; said locking and releasing means being retained in position for locking the valves in closed position by air pressure on said susceptible means, and being releasable upon lessening of said air pressure for permitting concurrent movement of the valves to open position by water pressure upon said susceptible means.
11. A dry valve device for dry pipe systems, comprising a pressure chamber, a water chamber, a chamber intermediate between said chambers, a dry valve between the pressure chamber and the intermediate chamber normally closed by pressure of the air in the pressure chamber, a wet valve between the water chamber and the intermediate chamber coactive with the dry valve, said dry valve including means collapsible by pressure of the air in said pressure chamber for retaining the valves in normal closed position, and extensible by lessening of said air pressure to permit concurrent movement of the valves to open position by water pressure from the water chamber.
12. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including convoluted means collapsible by pressure of the air in said pressure chamber for retaining the valves in normal closed position, and extensible by lessening of said air pressure to permit concurrent movement of the valves to open position by water pressure from the water chamber.
13. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, means for locking the valves in normal closed position, said dry valve including means collapsible by pressure of the air in said pressure chamber for retaining said locking means in position for holding the valves in normal closed position, and extensible by lessening of said air pressure for releasing said locking means to permit

concurrent movement of the valves to open position by water pressure from the water chamber.

14. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including means for locking the valves in normal closed position, and convoluted means collapsible by pressure of the air in said pressure chamber for retaining said locking means in position for holding the valves in normal closed position, and extensible by lessening of said air pressure for releasing said locking means to permit concurrent movement of the valves to open position by water pressure from the water chamber.

15. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including means for locking the valves in normal closed position, means collapsible by pressure of the air in the pressure chamber for retaining said locking means in position for holding said valves in normal closed position, and extensible by lessening of said air pressure for releasing said locking means to permit concurrent movement of the valves to open position by water pressure from the water chamber, and means for draining the intermediate chamber.

16. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including means for locking the valves in normal closed position, means collapsible by pressure of the air in the pressure chamber for retaining said locking means in position for holding said valves in normal closed position, and extensible by lessening of said air pressure for releasing said locking means to permit concurrent movement of the valves to open position by water pressure from the water chamber, and means for draining the intermediate chamber normally open to the atmosphere.

17. A dry valve device for dry pipe systems, comprising a pressure chamber, a water chamber, a chamber intermediate between said chambers, a dry valve between the pressure chamber and the water chamber normally closed by pressure of the air in said pressure chamber, a wet valve between the water chamber and the intermediate chamber coactive with the dry valve, said dry valve including means for locking the valves in normal closed position, means collapsible by pressure of the air in said pressure chamber for retaining said locking means in position for holding said valves in normal closed position, and extensible by lessening of said air pressure for releasing said locking means to permit concurrent movement of the valves to open position by water pressure from the water chamber, and means normally retained in open position by engagement with the wet valve for draining the intermediate chamber.

18. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including means for locking the valves in normal closed position, means collapsible by pressure of the air in said pressure chamber for retaining the locking means in position for holding said valves in normal closed position; and extensible by lessening of said air pressure for releasing said locking means to permit concurrent movement of the valves to open position by water pressure from the water chamber, and auxiliary means for admission of water from the water chamber to the intermediate chamber to expedite concurrent movement of the valves to open position by water pressure from the water chamber.

19. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including means for locking the valves in normal closed position, and primary and secondary means collapsible by pressure of the air in said pressure chamber for retaining said locking means in position for holding said valves in normal closed position, and extensible by lessening of said air pressure for releasing said locking means to permit concurrent movement of the valves

to open position by water pressure from the water chamber, said secondary means providing flexible connection between the dry and wet valves.

20. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, means for locking the wet valve to hold the wet and dry valves in normal closed position and unlockable to permit concurrent movement of the wet and dry valves, the dry valve including a collapsible and extensible means operable by pressure of the air in said pressure chamber and arranged when collapsed by pressure of said air to retain said locking means in position for holding the wet and dry valves in normal closed position, and when extended by lessening of said air pressure to release said locking means for unlocking the wet valve to permit concurrent movement of the wet and dry valves to open position by water pressure from the water chamber; said secondary convoluted means providing flexible air-tight connection between the dry and wet valves.

21. A dry valve device for dry pipe systems, comprising a pressure chamber, a water chamber, a chamber intermediate between said chambers, a dry valve between the pressure chamber and the intermediate chamber normally closed by pressure of the air in said pressure chamber, a wet valve between the water chamber and the intermediate chamber coactive with the dry valve, said dry valve including accordion diaphragm means collapsible by pressure of the air in said pressure chamber for retaining the valves in normal closed position, and extensible by lessening of said air pressure to permit concurrent movement of the valves to open position by water pressure from the water chamber.

22. A dry valve device for pipe systems, comprising a pressure chamber, a water chamber, a chamber intermediate between said chambers, a dry valve between the pressure chamber and the intermediate chamber and normally closed by pressure of the air in said pressure chamber, a wet valve between the water chamber and intermediate-chamber coactive with the dry valve, the dry valve including a primary and secondary accordion diaphragm, collapsible by pressure of the air in said pressure chamber on the primary diaphragm for retaining the valves in normal closed position, and extensible by lessening of said air pressure to permit concurrent movement of the valves to open position by water pressure from the water chamber; said secondary accordion diaphragm providing a flexible air-tight connection between the dry and wet valves.

23. A dry valve device for dry pipe sys-

tems, comprising a pressure chamber, a water chamber, a chamber intermediate between said chambers, a dry valve between the pressure chamber and the intermediate chamber and normally closed by pressure of the air in said pressure chamber, a wet valve between the water chamber and the intermediate chamber coactive with the dry valve, means for locking the wet valve to hold the wet and dry valves in normal closed position and unlockable to permit concurrent movement of the wet and dry valves, the dry valve including a collapsible and extensible means operable by pressure of the air in said pressure chamber and arranged when collapsed by pressure of said air to retain said locking means in position for holding the wet and dry valves in normal closed position, and when extended by lessening of said air pressure to release said locking means for unlocking the wet valve to permit concurrent movement of the wet and dry valves to open position by water pressure from the water chamber.

24. A dry valve device for dry pipe systems, comprising a pressure chamber, a water chamber, a chamber intermediate between said chambers, a dry valve between the pressure chamber and the intermediate chamber and normally closed by pressure of the air in said pressure chamber, a wet valve between the water chamber and the intermediate chamber coactive with the dry valve, means for locking the wet valve to hold the wet and dry valves in normal closed position and unlockable to permit concurrent movement of the wet and dry valves, said dry valve including accordion diaphragm means operative by pressure of the air in said pressure chamber and arranged when collapsed by pressure of said air to retain said locking means in position for holding the wet and dry valves in normal closed position, and when extended by lessening of said air pressure to release said locking means for unlocking the wet valve to permit concurrent movement of the wet and dry valves to open position by water pressure from the water chamber.

25. A dry valve device for dry pipe systems, comprising a pressure chamber, a water chamber, a chamber intermediate between said chambers, a dry valve between the pressure chamber and the intermediate chamber and normally closed by pressure of the air in said pressure chamber, a wet valve between the water chamber and the intermediate chamber coactive with the dry valve, means for locking the wet valve to hold the wet and dry valves in normal closed position and unlockable to permit concurrent movement of the wet and dry valves, the dry valve including a primary and a secondary accordion diaphragm, the secondary accordion diaphragm providing air-tight flexible

connection between the dry and wet valves, said diaphragm being operative by pressure of the air in said pressure chamber on the primary diaphragm and arranged when collapsed by pressure of said air to retain said locking means in position for holding the wet and dry valves in normal closed position, and when extended by lessening of said air pressure to release said locking 5 means for unlocking the wet valve to permit concurrent movement of the wet and dry valves to open position by water pressure from the water chamber.

26. A dry valve device for dry pipe systems, comprising a pressure chamber, a water chamber, a chamber intermediate between said chambers, a dry valve between the pressure chamber and the intermediate chamber and normally closed by pressure 10 of the air in said pressure chamber, a wet valve between the water chamber and the intermediate chamber coactive with the dry valve, toggle means for locking the wet valve to hold the wet and dry valves in normal closed position and unlockable for permitting concurrent movement of said valves, said dry valve comprising means collapsible by pressure of the air in said pressure chamber for retaining said toggle means in position 15 for holding the valves in normal closed position, and extensible by lessening of said air pressure for releasing said toggle means for unlocking the wet valve to permit concurrent movement of the valves to open position by water pressure from the water chamber.

27. A dry valve device for dry pipe systems, comprising a pressure chamber, a water chamber provided with a locking-groove in the interior thereof, a chamber intermediate between said chambers, a dry valve between the pressure chamber and the intermediate chamber and normally closed by pressure of the air in said pressure chamber, a wet valve between the water chamber and the intermediate chamber coactive with the dry valve and provided with a collar having apertures therein, toggle means for locking the wet valve to hold the wet and dry valves in normal closed position and unlockable for permitting concurrent movement of said valves, said dry valve comprising means collapsible by pressure of the air in said pressure chamber for retaining said toggle means in position for holding the valves in normal closed position and extensible by lessening of said air pressure for releasing said toggle means for unlocking the wet valve to permit concurrent movement of the valves to open position by water pressure from the water chamber; said toggle means comprising a stem fixedly secured to collapsible portion of the dry valve and provided with a head having a groove therein, and spring retained toggle-arms engaging

at their inner ends the groove in said head and extending through the apertured collar of the wet valve and engaging at their outer ends said locking-groove of the water chamber.

28. A dry valve device for pipe systems, comprising a pressure chamber, a water chamber, a chamber intermediate between said chambers and provided with an aperture through the wall at the bottom thereof and communicating with the atmosphere, a dry valve between the pressure chamber and the intermediate chamber and normally closed by pressure of the air in said pressure chamber, a wet valve between the water chamber and the intermediate chamber coactive with the dry valve and provided with a laterally extending lug, means for locking the wet valve to hold the wet and dry valves in normal closed position and unlockable for permitting concurrent movement of said valves, said dry valve comprising means collapsible by pressure of the air in said pressure chamber for retaining said locking means in position for holding the valves in normal closed position, and extensible by lessening of said air pressure for releasing said locking means for unlocking the wet valve to permit concurrent movement of the valves to open position by water pressure from the water chamber, and means for draining the intermediate chamber; said means for draining comprising a valve member provided with a spring controlled stem having a head for engaging said aperture of the intermediate chamber, the head having a groove therein for engagement therewith of said lug of the wet valve, and said draining means being normally retained in open position by engagement of said head with said lug of the wet valve.

29. A dry valve device for pipe systems, comprising a pressure chamber, a water chamber, a chamber intermediate between said chambers, a dry valve between the pressure and intermediate chambers comprising a disk closure member provided with an aperture therethrough and a recess adjoining said aperture, the dry valve normally being closed by pressure of the air in said pressure chamber, a wet valve between the water chamber and the intermediate chamber coactive with the dry valve and having a secondary aperture therethrough communicating with the water chamber, means for locking the wet valve to hold the wet and dry valves in normal closed position and unlockable for permitting concurrent movement of said valves, means collapsible by pressure of the air in said pressure chamber for retaining said locking means in position for holding the valves in normal closed position, and extensible by lessening of said air pressure for releasing said locking means for unlocking the wet valve to permit concurrent movement of said valves.

current movement of the valves to open position by water pressure from the water chamber, and means for expediting admission of water into the intermediate chamber; said means comprising a spring controlled valve member reciprocatable between said disk closure member and the wet valve and having a stem with a stem-end engaging the

aperture and recess of the disk closure member and a closure head engageable with said 10 secondary aperture of the wet valve.
